AUTOMATIC FEEDING DEVICE

Zebulon L. White, Parkville, and Werner Buchal, Kingsville, Md., assignors to The Glenn L. Martin Company, Middle River, Md., a corporation of Maryland

Application July 21, 1945, Serial No. 606,300

3 Claims. (Cl. 89—33)

1

Our invention relates to an automatic feeding device, and particularly to a force feed device such as may be used in the supplying of ammunition to an automatic gun.

It has been recognized for some time that where continuous ammunition feed is employed to supply a gun located a considerable distance from the source, a force feed device is necessary to help propel ammunition toward the gun. The device of this invention provides an automatic power driven feeder that can be located at any point along the ammunition track. This feature allows of ready application at feasible points along the track as determined from the engineering viewpoint as to where the greatest load is to be overcome or from the designer's viewpoint as to space allotment. This is possible due to the fact that the booster of our invention requires no complicated synchronizing controlling equipment but can be installed any place where suitable support and a power supply can be provided, the unit being self-contained and having an operating switch formed as an integral part thereof. It is a novel feature of our device that actuation of the energizing switch is controlled by the tension existing on the articles to be moved at the immediate point where the booster action is desired. In this manner our invention provides a mechanism whereby articles such as ammunition, or the like, can be maintained ready for immediate forward movement at a given predetermined stress irrespective of the slope at which the track is positioned. None of which novel features are to be found in the feeding devices of the prior art.

When used in its preferred embodiment as an automatic power driven ammunition feeding device our invention utilizes the power derived from an electric motor to preload ammunition along an ammunition track between the feeder and the gun as controlled by a torque responsive switch arranged as an integral part of the device, whereas formerly it has been customary for the gun to overcome the resistance inherent in such a system sufficiently to pull the ammunition to itself. In the practice of our invention, we have discovered a means of urging the ammunition toward the gun at a preloaded force in such a manner that the torque on the gun is practically eliminated. In this way, we are enabled to locate both the ammunition supply and the ammunition feeding device or devices, at varying distances from the gun without in any way impairing the efficient operation of the gun. When a plurality of our devices are used along a track

2

to feed a gun, each feeding device may well operate independently and may be separately adjusted to supply the amount of force needed at any given point; the driving force of each device being limited by the amount of preloading required to advance the ammunition to the next feeding device.

It is obvious that identical or similar problems may be met in any number of article feeding systems and that our invention is equally capable of advantageous use in such systems.

It is among the objects of our invention to provide a force feeding device for feeding ammunition through an ammunition track, or a like supply chute, to an automatic gun, which device consists of a driving shaft arranged to be driven by an electric motor energized by a torque controlled switch, an overrunning clutch positioned to be rotated by the shaft, sprockets arranged to engage the ammunition in the ammunition track and be rotated by the drive shaft operating through the overrunning clutch to force the ammunition toward the gun and yet be free to be rotated in the same forward direction by the ammunition drawn by the normal pull of the gun.

A further object of our invention is to provide a feed control mechanism for use with an automatic gun to which ammunition is fed through a track wherein the demand of the gun for ammunition is anticipated by preloading the supply of ammunition in the track toward the gun by an electric power unit and a drive engaging the ammunition, which drive includes a load responsive switch to energize the power unit when the torque of the preloaded ammunition drops in response to gun operation below a certain predetermined point and again deenergize the power unit when a predetermined stress is established in the preloaded ammunition.

40 A still further object of our invention is to provide an ammunition feeding device for a gun that automatically draws ammunition from a supply track or chute, said feeding device comprising a shaft driven by an electric motor, ammunition engaging sprockets arranged to be rotated through driving springs positioned between the drive shaft and the sprockets, a torque controlled switch formed as an integral part of the feeding device wherein a contactor is displaced from an insulating segment when the sprockets move the shaft forwardly through a limiting angle of rotative motion so as to complete the electric circuit to the driving motor whereby it is energized and rotates the drive shaft operating through the overrunning clutch to rewind the

driving springs against the torque of the ammunition engaged by the sprockets to a predetermined tension, at which point the contactor of the torque controlled switch is moved to a position on the insulating block so as to deenergize the driving motor.

A further object of our invention is to provide an article feeding system comprising a track and a power unit arranged to impose a predetermined article advancing force upon an article urging it along the track.

Other and further objects of our invention are apparent from the following description and from the accompanying drawings, wherein:

Figure 1 is a diagrammatic view showing our feeder unit installed in a gun feeding system;

Figure 2 is a side view of our feeder unit;

Figure 3 is a sectional view of our feeder unit taken on the line 3—3 of Fig. 2;

Figure 4 is a sectional view enlarged to show the interior construction of a portion of our feeder unit;

Figure 5 is a cross-sectional view at a reduced scale taken on line 5—5 of Fig. 4 showing the switching mechanism;

Figure 6 is a cross sectional view taken on line 6—6 of Fig. 4;

Figure 7 is a detail showing of one portion of our switching mechanism;

Figure 8 is a view showing a modified form of our feeder unit installed in an article feeding system;

Figure 9 shows a modification of one detail of the mounting sprocket; and

Figure 10 is a view taken on line 10—10 of Fig. 4 and shows the gear assembly partially cut away to illustrate the overrunning clutch.

Our invention is illustrated in the environment of a machine gun and supply assembly wherein a machine gun 1 receives its supply of ammunition from a track 8 leading from an ammunition box 9 located at some point more or less remote from the gun and past an ammunition feeder unit 10.

This unit includes a motor 11 positioned adjacent a gear box 12, which houses a one-way gear train 12a—e arranged for operation by the motor and adapted to rotate a shaft 13 in a given direction. In Figures 4 and 10 we have shown a conventional form of overrunning clutch such as may be used in our invention. Here a motor driven worm 12a rotates a gear 12b through which passes the shaft 13. Between the shaft 13 and the gear 12b is a clutch unit comprising an outer member 12c adjacent the gear 12b, an inner member 12d adjacent the shaft 13 and provided with a plurality of spaced pockets, and balls 12e carried between the outer and inner members. As shown in Figure 10 the clutch unit allows the shaft 13 to freely rotate in a clockwise direction, as the ammunition is being advanced by the gun, the balls 12e dropping into the pockets of the inner member 12d. However, when the motor is energized to meet an increased demand for ammunition so as to rotate 12a which in turn rotates gear 12b, the balls 12e assume a wedged driving position between the walls of the inner and outer members of the clutch unit providing powerized drive of shaft 13.

Mounted on shaft 13 are two ammunition impellers arranged as sprockets 17 spaced apart for spaced engagement with ammunition carried in the track 21. Spaced outwardly of each of the sprockets 17 at the ends of the shaft 13

are placed discs 14 formed with a series of spaced holes 16a extending therethrough. The discs 14 are secured to the shaft for rotation therewith by cap screws 15 screwed into the ends of said shaft. Between the discs 14 and sprockets 17 are placed connecting springs 16 coiled around the shaft 13. Each of said springs 16 are arranged with its inner end connected to one of said sprockets and its outer end inserted through one of said holes 16a formed in the discs 14 as selected to place the spring under sufficient tension to rotate the sprockets 17 against ammunition as hereinafter described.

Sprockets 17 have an integral barrel portion 17a formed with a pair of spaced outwardly extending, oppositely positioned teeth 17b. A collar 17c is adapted to idle on the shaft 13 between the barrel portion 17a and the disc 14. At its outer edge the collar is notched to receive a lug 14a integral with the disc 14 to prevent relative movement between the collar and disc. At its inner edge the collar 17c is provided with a pair of spaced, oppositely positioned teeth 17d adapted to interfit between the teeth 17b of the sprocket barrel portion. Between each tooth 17d and each tooth 17b is a space of a few degrees, hereinafter referred to as the limiting angle.

The sprockets 17 idle on the shaft, and the inner end of each spring 16 is secured to the adjacent sprocket whereby the winding of the spring by the motor will result in the rotation of the sprocket.

The feeder unit is mounted on a hanger 18 secured at its ends as by bolts 19 to a pair of brackets 20 in turn mounted on the sides 21 of the ammunition track 8 to which they are secured. The sides 21 are parallel to and slightly spaced from the hanger 18. The sprockets 17 each rotate in the space between the hanger and the sides 21 of the track 8, their teeth thereby engaging the ammunition carried by the belt in the track.

The current to the motor is controlled by a switching mechanism which is contained in a housing 23 which is disposed inwardly of one of the sprockets 17 (see Fig. 5). The mechanism is connected by suitable leads (not shown) to the motor 11, which is, in turn, connected to any suitable current supply and includes a circular slip ring 25 within and immediately adjacent, but insulated by insulation 35 from the wall of the housing 23 and sprocket 17. The sprocket 17 and slip ring 25 are electrically connected in the supply circuit of motor 11 so as to control the operation of the latter. This operation is accomplished by a circuit closing means adapted to electrically connect the slip ring to the sprocket wall 29 which in turn forms part of the circuit to the motor 11 (see Figure 5). This circuit closing means is provided by the spring brush 27 and contactor 28 carried by the shaft 13 as part of the rotating assembly 26. The rotating assembly 26 is mounted on the shaft 13 centrally of the slip ring 25 and insulated from the shaft by blocks 24 and carries the spring brush 27, so that as the shaft 13 revolves the brush 27 moves in contact with the slip ring 25 throughout the entire cycle of the rotating member. The contactor 28 is also carried by the rotating assembly 26 in contact with the wall 29 of the sprocket whereby the current, received through the brush 27, is conducted to ground, thereby completing the circuit to the motor. A non-conducting strip 30 is embedded in the wall 29 (see Figs. 5 and 7) for engagement

with the contactor 28 when forward motion of the sprocket 17 ceases due to resistance of the ammunition in the track becoming greater than the torque imposed by the spring. When the forward movement of the sprocket 17 ceases, the teeth 17b also cease to rotate. The revolving shaft thereby urges the collar 17c and teeth 17d through the limiting angle and toward the teeth 17b (see Fig. 6). This closing movement is opposed by the resistance of the now fully loaded spring 16. As the teeth 17d approach within a predetermined distance of the teeth 17b the contactor 28 is positioned on the non-conductor strip 30 thereby breaking the circuit and deenergizing the motor. As the ammunition is removed by firing of the gun, or a like removal such as when the gun is being unloaded, resistance of the ammunition to being moved in a forwardly direction is decreased allowing sprocket 17, under the urge of spring 16 in its tensed condition, to rotate in a clockwise direction through the limiting angle of free play between teeth 17b and 17d. This relative movement of sprocket 17 is sufficient to move contactor 28 off the non-conductor strip 30 completing the electrical circuit and energizing motor 11 causing it to rotate shaft 13.

The operation of our invention is as follows: The device is used to transmit ammunition for a machine gun along a track from the ammunition box to the gun. It is a feeder mechanism designed to force the ammunition all or part of the way along the track, thereby helping or eliminating the need for the gun as a source of ammunition advancing force.

This forcing action is supplied by the spring 16, which is kept under a constant tension, through the sprocket 17 which is stalled against ammunition solidly packed along the track 8. When the gun 7 begins firing it takes ammunition out of the track 8 and the spring 16 commences to unwind. As the sprocket begins to turn in response to the spring and as permitted by ammunition use, the contactor 28 is moved off the insulating strip 30, thereby reenergizing the motor; the operation of the motor rotates the shaft 13 to drive sprockets 17 as long as ammunition can be moved forwardly. On stoppage of ammunition movement the motor drive force is sufficient to overcome the established tension in spring 16 to effect movement of the shaft assembly relative to the stopped sprockets and advance the contactor 28 onto the insulating strip 30 and thereby disconnect the electrical circuit to motor 11.

The spring 16 is constructed and arranged so that it will maintain a constant predetermined tension on the sprocket, which is below that load required to stall the motor. Since the motor, in most circumstances, runs faster than is necessary for the feeding of ammunition it keeps the spring fully wound, and when the gun stops firing, the motor winds the spring completely, thereby operating the switching mechanism to deenergize the motor.

During the firing of the gun the operation of the motor in cooperation with the spring may in a measure be automatically synchronized to the feed speed of the gun. The construction and arrangement of the springs permits this without excessive stopping and starting of the motor. The energy stored in the spring urges the ammunition along the track. This urge if exceeding the demand in turn causes the ammunition belt to bind in the track, thereby loading the motor and reducing its speed to approximately gun speed. The additional friction resulting from the con-

stant accumulation of ammunition in the track for the gun to draw on thus acts to slow down the motor to the gun speed without employment of the switching device. Thus we are able to make constant use of the full torque of the motor, and to apply constant pressure on the ammunition in the track.

In addition to relieving the drag on the gun, our feeder unit reduces the strain on the links of the track by more equally allocating the pressure and tension thereon.

Due to the compact nature of our feeder unit, it may be employed at any position along a track, even where a sharp turn in the track is required as when feeding into the gun from below.

When it is desirable, as where the feeder is positioned near the gun, the spring 16 may be made considerably weaker than that above described so that it will act only to actuate and deenergize the motor. In this adaptation the sprockets 17 would rotate with the shaft 13 (see Fig. 3). In this way the forward movement of ammunition through the track between the feeder and the gun would be left entirely to the pull of the gun, the feeder unit acting only to pull ammunition from the box to the feeder. Unlike previous feeder units, however, our invention would not leave the control of the motor to the pull of the gun, but would instead control it by the force of the springs 16.

In Figure 8 we have diagrammatically shown a modification of our feeder unit in use in an article conveying system capable of handling other types of articles. Here articles 31 are urged along a track 8' by a sprocket 17' rotated in a given direction by a shaft 13' which is actuated by a torque spring 16' which in turn is actuated by a co-axial shaft 13a, the shaft 13a being driven by a one way gear train housed in gear box 12' which is operated by a motor 11'. The motor is controlled and operated as above described, the switch mechanism being mounted in the switch box 23'.

In Figure 9 we have shown a modified form of mounting of the sprocket whereby a hub 32 is securely fastened by a bolt 33 to the shaft 13, and to which the sprocket 17 may be removably secured as by bolts 34. In this way, a sprocket may quickly be transferred from one shaft to another where a change of position or feeding is for any reason required.

It is to be understood that certain changes, alterations, modifications and substitutions can be made without departing from the spirit and scope of the appended claims.

55 We claim:

1. An ammunition feeder and track for force feeding ammunition toward an automatic gun, comprising, spaced side members for positioning the ammunition, a housing carried by the side members and spaced from the positioned ammunition, a drive shaft mounted in said housing transversely to the side members, irreversible power transmission means for rotating said shaft comprising motor means carried by said housing, a worm driven by said motor means, and a worm gear meshing with said worm, an overrunning clutch interposed between said worm gear and said drive shaft, at least one sprocket mounted on said shaft and proportioned to engage said ammunition, said sprocket being limited in angular movement relative to the shaft by spaced abutments carried by said sprocket and shaft, a spring connecting said sprocket and shaft constructed and arranged as to urge said sprocket forwardly a few degrees only to effect displace-

ment between said sprocket and said shaft as limited by said abutments; a rotary switch mechanism mounted adjacent said sprocket having a contact member carried by said shaft and radially placed relative to said shaft and adapted for movement away from an insulating member mounted on said sprocket, upon initial movement of ammunition in the track toward said gun, to energize said motor means upon displacement between the sprocket and shaft to actuate the sprockets for movement of the ammunition in said given direction upon initial withdrawal of ammunition from the track by the gun.

2. A booster mechanism for controlling the feed of ammunition in a track to an automatic gun comprising, a track section having spaced sides for positioning ammunition, a housing mounted adjacent said track section, a drive shaft carried by said housing with ends of said shaft extending therefrom, an irreversible motor drive mechanism associated with said shaft and constructed and arranged to rotate said shaft in one direction, an overrunning clutch interposed between said motor drive mechanism and said shaft, sprockets rotatably mounted on said drive shaft for independently spaced engagement with the ammunition, at least one of said sprockets being formed with a spaced abutment adjacent the shaft, said shaft being provided with a corresponding abutment arranged for engagement with the sprocket abutment to provide for limited rotative movement a few degrees only between said sprocket and drive shaft, spring means constructed and arranged to urge said sprocket to rotate in advance of said drive shaft, switch means comprising contacts carried by said shaft and said sprocket so arranged to energize the motor upon movement of said sprocket in advance of said drive shaft and to deenergize the motor upon movement of the shaft abutment toward engagement with the sprocket abutment, upon stoppage of said sprocket by the ammunition stopping in said track when the gun stops firing.

3. A feeder mechanism for forcing the movement of articles in an article advancing system comprising, an article positioning means arranged to expose a portion of said articles carried thereby for advancement in a given direction, a shaft spaced from the article positioning means, article impelling means mounted on said shaft adjacent the article positioning means and arranged for rotative engagement with said articles, an irreversible motorized drive means drivingly connected to said shaft, said drive means having motor disengaging means associated therewith to accommodate free forwardly rotation of the shaft relative to the drive means, spring means between the shaft and impeller so constructed and arranged to forwardly rotate the impeller relative to the shaft, abutment means carried by said impelling means and shaft limiting the relative movement therebetween, and switch means between said impelling means and said shaft responsive to relative movement therebetween to energize and deenergize the motor of said drive means.
